UNITED STATES PATENT OFFICE.

ALEXANDER KILPATRICK, OF ST. LOUIS, MISSOURI.

APPARATUS FOR CASTING PIPE.

SPECIFICATION forming part of Letters Patent No. 349,596, dated September 21, 1886.

Application filed April 29, 1886. Serial No. 200,604. (No model.)

To all whom it may concern:

Be it known that I, ALEXANDER KILPATRICK, of the city of St. Louis, in the State of Missouri, have invented a certain new and useful Improvement in Apparatus for Casting Gas and Water Pipes and other Long, Heavy Castings, of which the following is a full, clear, and exact description, reference being had to the accompanying drawings, forming part of this specification, and in which—

Figure 1 is a detail side elevation showing the lower part of a double flask with my improvement applied. Fig. 2 is an edge view of same. Fig. 3 is an under view of the bottom of the flask. Fig. 4 is a vertical section taken on line 4 4, Fig. 2, showing the lower ends of the patterns in place and the rings for forming the beads in place; and Fig. 5 is a similar view showing the patterns and rings removed and the core inserted and the lower end of the pipe. Fig. 6 is a perspective view of one of the bead-rings. Fig. 7 is a perspective view of one of the bead-ring seats removed.

My invention relates to an improvement in the apparatuses for casting water and gas pipes and other long, heavy castings; and my invention consists in features of novelty hereinafter fully described, and pointed out in the claim.

Referring to the drawings, A represents a flask, which I have shown as double, but which may be single, if desired, as the part to which my invention relates may be used on a single as well as on a double flask.

B represents the bottom of the flask, which is secured to the body by means of simple clamps C, as usual. Any well-known form of clamp can be used.

It has heretofore been the practice in manufacturing these pipes or castings, where it is necessary to form a bead on the lower end, to form the recess of the bead in the mold by placing the flasks on what is termed a "ramming-stand," with a ring or bead on the stand, which forms a recess in the mold to produce the bead when the pipe is cast. With this process it is necessary to move the flask after the mold is formed, in order to remove the ring before the pipe is cast, to permit the bead to be formed on the pipe, which results in considerable labor, loss of time, and cost, resulting from handling the heavy flasks. It has also been common heretofore to place what is

termed "sectional chill-rings" in a flask-bottom held in a suitable seat, with grooves in these sectional rings to form the bead on the pipe, these rings being made in sections to allow their removal from the bead after the pipe is cast. There are objections to this method also, among which is that the rings soon become destroyed by the hot metal, and, moreover, are liable to become lost, and it requires considerable time to handle and put them in place and clean the sand and dirt out of the grooves.

To avoid these difficulties is the object of my invention, and to this end I removably secure in the opening of the flask-bottom seats D, that hold or support rings E, that form the recesses in the mold to produce the beads on the ends of the pipes. I have shown the seats D held in place by means of inclined lugs F thereon, which are turned to enter beneath lugs or ears G on the bottom, as shown in Figs. 3 and 5. The inclination of these lugs F is shown in Fig. 7, the object being that, as the seats are turned from the position shown on the right-hand side of Fig. 3 to that on the left-hand side of Fig. 3, the lugs F will engage beneath the lugs G on the bottom, and thus securely hold the seats in place. The upper or inner surfaces of the seats are preferably recessed slightly at I, as shown in Figs. 4, 5, and 7, to receive the bead-rings E and hold them centrally on the seats.

The operation is as follows: Before commencing to ram the flask the seats D are put and held in place, as above described, with the rings E in the recesses I. The patterns J are then inserted into the flasks, the lower ends of the patterns fitting in the tapering openings of the seats D, as shown in Figs. 4 and 5. The ramming is then commenced, filling the space L between the pattern and the inner wall of the flasks with a sand mold, M, as shown on right-hand side of Fig. 4. After the ramming has been carried on for some time, or after it is finished, if desired, the seats D are removed by turning them from the position shown on the left-hand side of Fig. 3 to that on the right-hand side of same figure, and the bead-rings removed from the seats, when the latter are replaced and turned to the position shown in Fig. 3. The patterns J are then removed and the cores N, as shown

in Fig. 5, inserted, forming a space between them and the mold to receive the molten metal to form the pipe O, as shown in Fig. 5. The bead-rings having been removed, a recess is 5 formed in the lower ends of the molds, as shown at P, Fig. 5, and into these recesses runs the molten metal, forming beads on the lower ends of the pipes, as illustrated in said figure. The casting now having been completed, the pipes are removed in the usual manner. It will thus be seen that a perfect bead will be formed upon the lower end of the pipe, and that it is done without moving the flask after the ramming commences, and is also 10 done without the use of sectional or grooved rings.

The seats D are quite light, and can be conveniently removed and replaced to allow the removal of the rings E, and this removal of 15 the seats to get rid of the rings can take place when the mold is only partly made—say three or four feet high in the bottom of the flask—for it will then form a perfect resistance to the ramming process, so that the seats may be re-

25 moved and inserted without stoppage either of the ramming process or process of casting.

Another disadvantage of the use of this means over sectional chill-rings exists in the fact that it is practically impossible to make the sectional rings fit so snugly together, especially after being used a few times, that there will not be a sufficient space between the different sections for the molten metal to enter a short distance at least, thus forming upon the bead of the lower end of the pipe sharp fins, 30 which are objectionable, and which are avoided by my improved method.

35 I claim as my invention—

The combination of the flask A, bottom B, lugs G on the bottom, seat D, lugs F on the 40 seat, to engage the lugs on the bottom, and bead-ring E, substantially as and for the purpose set forth.

ALEXANDER KILPATRICK.

In presence of—

GEO. H. KNIGHT,
EDW. S. KNIGHT.
